UNITED STATES PATENT OFFICE.

RICHARD S. BRYANT, DECEASED, LATE OF CLEVELAND, OHIO, BY OTTO H. JOBSKI, OF CLEVELAND, AND JAMES H. GRISWOLD, OF EAST CLEVELAND, OHIO, SPECIAL ADMINISTRATORS, ASSIGNEES TO THE STANDARD WELDING COMPANY, OF CLEVELAND, OHIO, A CORPORATION OF OHIO.

MACHINE FOR SIZING TRANSLIT RIMS.

1,268,789.

Specification of Letters Patent. Patented June 4, 1918.

Application filed November 18, 1916. Serial No. 131,102.

To all whom it may concern:

Be it known that we, OTTO H. JOBSKI and JAMES H. GRISWOLD, both citizens of the United States, and respectively residents of 5 Cleveland and East Cleveland, county of Cuyahoga, State of Ohio, special administrators of the estate of RICHARD S. BRYANT, late a citizen of the United States, and resident of Cleveland, Ohio, deceased, (as by 10 reference to the duly-certified copy of letters of administration heretofore filed for the purpose of record will more fully appear,) believe said RICHARD S. BRYANT to have invented 15 a new and useful Improvement in Machines for Sizing Transplit Rims, of which the following is a specification, the principle of the invention being herein explained and the best mode in which it was contemplated applying said principle, so as 20 to distinguish it from other inventions.

The present improvements relate to a device for sizing a transplit annulus and are particularly designed for use in sizing vehicle wheel rims of the transplit type. It 25 is customary in this operation to place the annulus upon a suitable mandrel of such a size as to permit the ends of the annulus to abut against each other. When the annulus is in such position, other means, preferably 30 a plurality of radially movable blocks compress the annulus against the mandrel, thus properly sizing the same and rounding out any irregularities in the shape of the annulus. The difficulty with such a machine 35 is that during this compression the ends of the annulus are forced against each other, oftentimes in such a way as to mar these two ends, and it is to prevent this injury to the ends or edges of the annulus that the 40 present invention is designed. To the accomplishment of the foregoing and related ends, said invention, then, consists of the means hereinafter fully described and particularly pointed out in the claims.

25 The annexed drawings and the following description set forth in detail certain mechanism embodying the invention, such disclosed means constituting, however, but one of various mechanical forms in which the 30 principle of the invention may be used.

In said annexed drawings:-

Figure 1 is a broken plan view of a tire-setting machine of well-known type, showing the present improvements incorporated

therein; Fig. 2 is a vertical section of such machine, the plane of the section being indicated by the line 2—2, Fig. 1; Fig. 3 is a plan view on a larger scale than Fig. 1, of the portion of the machine which includes the aforesaid improved features of construction; Fig. 4 is a vertical section taken on the plane indicated by the line 4—4, Fig. 3; and Fig. 5 is a similar vertical section taken on a parallel plane as indicated by the line 5—5, Fig. 3.

In the several figures there is shown a mandrel 1, of suitable material, which will preferably be formed of a diameter slightly greater than the desired internal diameter of the annulus when finished. Upon this 70 mandrel there is placed the annulus 2, (see Fig. 2), and by reason of the diameter of the mandrel, the ends of the annulus will not contact but will be separated by a slight space. The present invention is, of course, 75 designed to operate upon any type of annulus, but as stated above has been particularly intended for use in sizing transplit rims of the type used on motor vehicle wheels which must be very accurately dimensioned and which must not be injured at the ends during the operation, and it is 80 such a rim which is shown in Fig. 2 of the drawing.

Any desired means may be employed for 85 compressing or sizing the rim upon the mandrel, such for example, as a plurality of radially movable blocks 4, of which several are shown in Figs. 1 and 2, where the features of construction of interest herein are 90 shown as incorporated in a tire-setting machine of otherwise familiar construction. These blocks are operated by any desired means, usually by fluid pressure of some sort, as indicated in the figures just referred to, 95 although other means for compressing the block may be used if desired, without affecting the present invention, so long as a single one of said blocks, like the one designated 5, is employed to compress the parts of the rim 100 adjacent to its ends.

It is not necessary that the block 5 move in an exactly radial direction, and if desired, it may move in a direction at a slight angle to a radial line passing through the 105 center of the mandrel and the block. In the present illustration, this is the movement given to the said block 5, and is occa-

sioned by the nature of the ends of the rim 2, since this rim is cut at a slight angle to a radial line passing through the point of cutting or upon a plane forming a sector 5 cutting the annulus. The block 5 is therefore made to move in a direction parallel with the cut edges of the rim and is provided with a shield or spacing member in the form of a relatively thin plate 6, fixed in a re- 10 movable holder 7, and having a pointed end, as shown. This plate or shield is adapted upon inward movement of the block to lie between the ends of the rim, and to properly space the same in order to prevent 15 marring or jamming of these two ends against each other during the compression of the rim upon the mandrel. The size of the spacing shield 6, is determined by the diameter of the mandrel with respect to the 20 desired diameter of the rim, this shield being proportioned to contact with the ends of the rim when the latter is forced smoothly and evenly against the mandrel at all points. The mandrel 1, is provided with a 25 suitable aperture 8, formed as a slot between two blocks 9, 9, set in spaced relation in a recess 10 in said mandrel, and there held in place by means of set bolts 11, 11, adapted to receive the projecting end of 30 the spacing shield as the latter moves through the rim upon the compressing movement of the blocks 4.

In a tire setter of the kind in hand the compression blocks are loosely connected to 35 the actuating plungers and it is thus possible for the block 5 to move in a plane aligned with the plane of the ends of the rim, although the other blocks operate radially as usual. This is possible since the lateral, 40 or rather circumferential movement imparted to the block 5 by its plane of movement is too slight to bring it into the radial path of movement of the adjacent blocks.

By means of the present machine it is 45 possible to properly size any trans-split annulus of the type shown without in any way injuring the ends of the annulus. In fact, the spacing shield cooperates with the block 5 to properly form the ends of the annulus 50 if they have been slightly compressed during any previous operation in the manufacture of the rim.

Other modes of applying the principle of my invention may be employed instead of 55 the one explained, change being made as regards the mechanism herein disclosed, provided the means stated by any of the following claims or the equivalent of such stated means be employed.

60 We therefore particularly point out and distinctly claim as the invention:—

1. In a device of the class described, the

combination of a mandrel adapted to receive thereon a trans-split annulus, said mandrel being of a diameter greater than 65 the internal diameter of such annulus, means for compressing the latter against said mandrel, and means abutting against the ends of such annulus for preventing deformation of the same during such compres- 70 sion.

2. In a device of the class described, the combination of a mandrel adapted to receive thereon a trans-split annulus, said mandrel being of a diameter greater than 75 the internal diameter of such annulus, means for compressing the latter against said mandrel, and a shield abutting against the ends of such annulus for preventing def- 80 ormation of the same during such compres- sion.

3. In a device of the class described, the combination of a mandrel adapted to receive thereon a trans-split annulus, said mandrel being of a diameter greater than 85 the internal diameter of such annulus, means for compressing the latter against said mandrel, and a shield operated by said means to space the ends of such annulus apart and prevent deformation of the same 90 during such compression.

4. In a device of the class described, the combination of a mandrel adapted to receive thereon a trans-split annulus, said mandrel being of a diameter greater than 95 the internal diameter of such annulus, a plurality of radially movable compression blocks operating to force such annulus against said mandrel, and a shield attached to one of said blocks and adapted to be inserted thereby between the ends of such annulus to properly space the same and prevent deformation during such compression. 100

5. In a device of the class described, the combination of a mandrel adapted to receive thereon an annulus, transplit in a plane forming a sector across the same, said mandrel being of a diameter greater than 105 the internal diameter of such annulus, a plurality of radially movable compression 110 blocks operating to force such annulus against said mandrel, a shield attached to one of said blocks, the ends of such annulus being positioned against said shield and said one block being thereby guided to move in 115 alinement with the plane of the ends of said annulus.

Signed by us this 6 day of November, 1916.

OTTO H. JOBSKI,

JAMES H. GRISWOLD,

Special administrators of Richard S. Bry-
ant, deceased.
